(57) **CLAIM**

The ornamental design for a knotless anchor, as shown and described.

DESCRIPTION

FIG. 1 is a perspective view of a knotless anchor showing our new design;

FIG. 2 is a front elevational view of the knotless anchor of FIG. 1;

FIG. 3 is a rear elevational view of the knotless anchor of FIG. 1;

FIG. 4 is a left-side elevational view of the knotless anchor of FIG. 1;

FIG. 5 is a right-side elevational view of the knotless anchor of FIG. 1;

FIG. 6 is a top plan view of the knotless anchor of FIG. 1; and,

FIG. 7 is a bottom plan view of the knotless anchor of FIG. 1.

The broken lines immediately adjacent the shaded areas represent the bounds of the claimed design while all other broken lines are directed to environment and are for illustrative purposes only; the broken lines form no part of the claimed design.
